UNITED STATES PATENT OFFICE

HENRY LANGE, OF QUINCY, ILLINOIS

DESIGN FOR A RANGE

Application filed May 23, 1932. Serial No. 43,879. Term of patent 7 years.

To all whom it may concern:

Be it known that I, HENRY LANGE, a citizen of the United States, residing at Quincy, in the county of Adams and State of Illinois, have invented a new, original, and ornamental Design for a Range, of which the following is a specification, reference being had to the accompanying drawing, forming a part thereof.

In the said drawing, the figure is a perspective view of a range showing my new design.

I claim:

The ornamental design for a range as shown.

In testimony whereof, I hereto subscribe my name this 14th day of May, A. D. 1932.

HENRY LANGE.
